SCREW JACK

Original Filed Sept. 25, 1923

INVENTOR

BY
Duell, Warfield & Duell
ATTORNEY

UNITED STATES PATENT OFFICE.

FRED HORACE WILDER, OF BRATTLEBORO, VERMONT, ASSIGNOR TO MILLERS FALLS COMPANY, OF MILLERS FALLS, MASSACHUSETTS, A CORPORATION OF MASSACHUSETTS.

SCREW JACK.

Application filed September 25, 1923, Serial No. 664,723. Renewed January 16, 1926.

To all whom it may concern:

Be it known that I, FRED HORACE WILDER, a citizen of the United States, residing at Brattleboro, in the county of Windham and 5 State of Vermont, have invented certain new and useful Improvements in Screw Jacks, of which the following is a full, clear, and exact description, such as will enable others skilled in the art to which it apper- 10 tains to make and use the same.

This invention relates to a jack and aims 15 to provide an improved device of this character.

It is an object of the present invention to 20 produce a jack which may be used for any desired purpose, and which will embrace a simple form of mechanism, thus furnishing an extremely rugged type of tool, in which mechanical difficulties will be reduced 25 to a minimum, aside from the fact that the tool lends itself to being manufactured at a nominal figure.

It is a further object of the invention to 30 provide an article of the character stated, 25 which may be operated to exert a pushing or lifting action, this operation being extremely simple and capable of accomplishment by any novice with a minimum of exertion.

A still further object of the invention is 35 that of furnishing a tool embracing a construction serving to prevent to the greatest extent the entrance of foreign particles into the mechanism thereof.

Another object is that of constructing a 40 jack in which those parts which are subjected to the greatest amount of wear may readily be renewed when it is found that the efficiency of the tool is impaired by this wear.

Other objects of the invention will in part 45 be obvious and will in part appear hereinafter.

The invention accordingly comprises the 50 features of construction combination of elements, and arrangement of parts, which 45 will be exemplified in the construction hereinafter set forth and the scope of the application of which will be indicated in the claims.

For a fuller understanding of the nature 55 and objects of the invention reference should be had to the following detailed description

taken in connection with the accompanying drawing, in which:

Fig. 1 is a front elevation of the improved jack with certain of the parts in section, 55

Fig. 2 is a fragmentary sectional view of a detail of construction, this view being taken at right angles to Fig. 1, and

Fig. 3 is a top plan view of one of the units forming a part of the jack mechanism. 60

Attention being particularly invited to Fig. 1, it will be seen that reference numeral 5 indicates the standard of the jack and that the pushing element thereof may embrace a contact portion or cap 6 affixed 65 to the upper end of a spindle 7, which latter extends into the standard.

Now with a view to providing means serving to move the spindle longitudinally of the standard, it will be noted that the former 70 may be provided with screw-threads 8 which are engaged by corresponding threads formed on a nut 9. Thus the nut serves to support the spindle and it will be obvious, assuming that these parts are rotated with 75 respect to each other, that the movement desired will be accomplished. In order, in turn, to properly support the nut upon the standard, the adjacent edges of these members may each be formed with an annular 80 groove within each of which there is disposed a removable liner 10, providing a ball race section, it being obvious that when suitable bearing balls 11 are arranged within the ball-race, the spindle operating means 85 will be capable of being readily moved with respect to the standard.

Operating means for the spindle moving means aforescribed, may be furnished in that a housing 12 is provided which rotatively encircles the nut as well as a portion of the standard, and this housing may be formed with an extension 13 presenting an opening 14 for a purpose hereinafter specified. In the present instance a pawl 90 and ratchet mechanism is incorporated in the housing 12 and nut 9, in that a ratchet is associated with the nut by forming the same with an annular series of radially extended teeth 15, while a pawl is carried by 100 the housing. This pawl may include a body 16 having a beveled face 17 at one of its

ends, and a stem 18 is secured to its opposite end and serves to slidably support the pawl upon the housing by passing through an opening formed in an extended portion 19 thereof and a spring 20 is interposed between the inner face of this extended portion and the pawl body, in order to normally force the latter into engagement with the teeth of the nut.

10 Thus, assuming that a suitable rod or tool handle is introduced into the opening 14 of the housing 12, and the latter is oscillated with respect to the standard, it will be obvious, further assuming that the spindle is 15 restrained against rotation, that rotation of the housing in one direction will cause a firm engagement between one of the faces of the pawl 16 and one of the teeth 15 of the nut 9, to thus rotate the latter, while a return 20 movement of the housing will cause the pawl merely to override these teeth so that a lost motion will result. Due to this movement of the parts, i.e., an intermittent rotation of the nut 9, the spindle and contact portions 25 carried thereby will be moved longitudinally of the standard in one direction. Conversely, if it is desired to move the parts in an opposite direction, it will be apparent that this may be accomplished by simply exerting a 30 pull upon the stem 18 by means of a knob 21, so that the stem is retracted to a point at which a pin 22 carried thereby rides beyond the edges of a slot 23 formed in the extension 19. When the parts have reached 35 this position, it will be obvious that the stem 18 may be turned by means of the knob 21 so that the pawl assumes a position in which the bevelled face 17 thereof extends in a direction opposite that in which it originally 40 extended, after which the knob 21 may be released in order to permit the pin 22 to again ride into the slot 23 thus locking the parts. An oscillation of the housing 12 in the manner already described will now cause lost 45 motion between the pawl and ratchet mechanism by that stroke, during which previously the pawl positively engaged the ratchet while movement in the opposite direction will cause lost motion between the pawl and ratchet. Still assuming that the spindle is 50 held against rotation, it will be obvious that this member will now be moved longitudinally of the standard in a direction opposite to that which it originally followed, thus 55 again achieving the results desired.

In order to prevent any accidental disarrangement of the parts, it will be seen as in Figs. 1 and 2, that the housing may be formed with an annular groove 24 in its inner face, while the standard 5 is formed with a corresponding groove 25 in its outer face, and at a point in line with the first named groove. A lock ring 26 may be disposed so as to extend partially within each of the 60 grooves 24 and 25 as brought out in Fig. 1.

and thus it will be evident that any material movement of the parts, other than in the proper manner, is prevented. When it is desired the detachment of these parts may be readily accomplished by simply introducing a suitable implement through the opening in the standard which communicates with the recess or groove 25. Thus the ring may be displaced so that a partial detachment 70 may be effected, subsequently to which the parts may be manipulated to entirely displace the operating member from the standard. Further, in order to prevent any improper movement of the nut 9 with respect to the parts with which it is associated, it 75 will be seen that the upper edge of the housing 12 may be inturned to provide a flange 27 and this flange may engage a shoulder 28 formed for this purpose in the upper edge 80 of the nut. Thus, in addition to the housing providing an operating means for the spindle moving mechanism, it will be noted that this element also serves as a restraining member to prevent any disarrangement of the 85 parts with respect to each other. 90

Finally, in order to prevent the entrance of particles of foreign matter into the jack, although permitting access to be had to the interior of the standard, it will be noted that the latter may be formed with an opening 29 in its base, which opening is reduced to provide a shoulder against which a closure plate 30 may bear, the plate being normally held in position by means of a lock ring 31 in engagement with both this member and the 100 side walls of the opening 29. In the event that the plate 30 is removed, it will be obvious that the inner end of the spindle 7 may be reached so that if it is desired to completely remove the latter from the tool, this 105 may be accomplished simply by withdrawing the stop pin 32 which normally serves, by contacting with a portion of the inner face of the standard, to prevent undue movement of the spindle in an outward direction. 110

In use it will be appreciated that according to the construction exemplified, the spindle 7 is normally held against rotation by the load upon the contact portion thereof, and this load may be moved by simply reversing the pawl in the manner aforescribed to cause the same to assume a position opposite to that shown in Fig. 1, so that by oscillating the housing the spindle moving means embraced by the nut 9 is intermittently rotated. When it is desired to return the parts to their normal position, a continued oscillation after the pawl has been again brought into the position shown in Fig. 1, will obviously effect this result, it 115 being noted, due to the aggregate length of the standard and housing that the spindle will be enclosed substantially in its entirety within the body of the jack when it is disposed in its normal or retracted position, it 120 125 130

being thus understood that a minimum of space is normally occupied by the jack. Incident to the manner in which all of the parts are enclosed, the entrance of foreign matter into the mechanism of the tool is prevented to a great extent and if the bearing provided by the ball race wears, it will be seen that this defect may readily be overcome by simply removing the liners 10 and

10 substituting therefor new liners.

Since certain changes may be made in the above construction and different embodiments of the invention could be made without departing from the scope thereof, it 15 is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall 25 therebetween.

Having described my invention, what I claim as new and desire to secure by Letters Patent, is:

1. A jack, including a standard, a spindle 30 carried by said standard, spindle moving means forming a part of said jack and co-operating with said standard, operating means for said moving means, said operating means being movable with respect to 35 said standard, said standard and operating means being formed with complementary grooves and means extending into both of said grooves for preventing accidental removal of said operating means from said 40 jack.

2. A jack, including a standard, a spindle 45 carried by said standard, spindle moving means forming a part of said jack and co-operating with said standard, operating means for said moving means, said operating means being movable with respect to said standard and a releasable locking ring 50 cooperating with said operating means and standard to normally retain all of said parts in properly correlated position.

3. A jack, including a standard, a spindle 55 carried by said standard, spindle moving means forming a part of said jack and coop-

erating with said standard, operating means for said moving means, said operating means being movable with respect to said standard, said standard and operating means being formed with complementary grooves and a lock ring extending into both of said grooves for normally retaining all 60 of said parts in properly correlated positions.

4. A jack, including in combination, a standard, a nut mounted to rotate on the upper end of the standard, a spindle threaded through the nut, a housing for the nut rotatably connected with the upper end of the standard, a pawl and ratchet connection between the nut and the housing, the rotatable connection between the housing and the standard including annular grooves in the adjacent faces of the housing and the standard, and a locking ring engaging the grooves.

5. A jack, including a standard, a spindle 75 carried by said standard, means for causing a movement of said spindle relatively to said standard, said means and standard being formed with complementary recesses, one of said elements being formed with an opening 80 affording access to the chamber provided by said recesses, and means common to both of said recesses for preventing an accidental detachment of the parts of said jack, said opening affording access to said last-named 85 means.

6. A jack, including, in combination, a standard, a lifting member and operating means therefor carried by said standard, said standard and operating means being 90 formed with complementary recesses, and means common to both of said recesses for preventing a displacement of said parts.

7. A jack, including a standard, a spindle 95 carried by said standard, means for causing relative movement of said parts, said means and standard being formed with complementary recesses, and one of said elements being formed with an opening affording access to the chamber provided by said recesses, and a ring disposed within said chamber for preventing a relative displacement 100 of the recessed parts.

In testimony whereof I affix my signature.

FRED HORACE WILDER.
